PACKING SHEET FOR ELECTRICAL RESISTORS

Gilbert R. Chadbourne, Oakland, Maine, assignor to
Keyes Fibre Company, Portland, Maine, a corporation
of Maine

Application October 24, 1955, Serial No. 38,530

Term of patent 14 years

(Cl. D58—13)

Fig. 1

Fig. 2

Fig. 3

Fig. 4

Fig. 1 is a top plan view of a packing sheet for electrical resistors embodying my new design;

Fig. 2 is a longitudinal sectional view taken on line 2—2 of Fig. 1;

Fig. 3 is a cross-sectional view taken on line 3—3 of Fig. 1;

Fig. 4 is a fragmentary longitudinal cross-section view thereof, taken on the line 4—4 of Fig. 1.

What is claimed:

The ornamental design for a packing sheet for electrical resistors, as shown.
